FIG.5

FIG.6

FIG.7

FIGURE 1 is a side elevation of a velocipede showing my new design, the characteristic feature residing in the portion shown in full lines;

FIGURE 2 is an enlarged plan view looking in the direction of the arrows 2—2 of FIGURE 1;

FIGURE 3 is an enlarged rear end view looking in the direction of the arrows 3—3 of FIGURE 1;

FIGURE 4 is a rear end view of the lower portion of the velocipede shown in FIGURE 1 and drawn to the same scale as FIGURE 1;

FIGURE 5 is an enlarged view corresponding to the content of FIGURE 3 but looking in the opposite direction, that is, toward the rear of the velocipede;

FIGURE 6 is an enlarged bottom view corresponding to the content of FIGURE 2 but looking in the opposite direction; and

FIGURE 7 is an enlarged end view corresponding to the content of FIGURES 2, 3, 5 and 6 and taken from

the side of the velocipede opposite of that shown in FIGURE 1.

Portions of the broken line showing the velocipede have been omitted from the views for convenience of illustration.

I claim:

The ornamental design for a velocipede, substantially as shown and described.
